DESIGN FOR A JEWELRY FINDING

Theodore C. Steinman, New York, N. Y., assignor
to The Committee for the Celebration of the
President's Birthday for the National Founda-
tion for Infantile Paralysis, Inc., New York,
N. Y.

Application December 17, 1941, Serial No. 104,677

Term of patent 3½ years

To all whom it may concern:

Be it known that I, Theodore C. Steinman, a
citizen of the United States of America, residing
in New York city, county of New York, and State
of New York, have invented a new, original, and
ornamental Design for a Jewelry Finding, of
which the following is a specification, reference
being had to the accompanying drawing, forming
part thereof.

Fig. 1 is a plan view of a jewelry finding show-
ing my new design.

Fig. 2 is an edge view thereof.

I claim:

The ornamental design for a jewelry finding,
substantially as shown.

THEODORE C. STEINMAN.
